The ornamental design for a chair, as shown and described.

DESCRIPTION

FIG. 1 is a front elevational view of a chair showing my design;

FIG. 2 is a rear elevational view of the chair;

FIG. 3 is a right side elevational view of the chair;

FIG. 4 is a top plan view of the chair;

FIG. 5 is a bottom plan view of the chair;

FIG. 6 is a cross-sectional view of the chair; taken along line 6-6 in FIG. 4; and,

FIG. 7 is a right side elevational view of the chair with the seat of the chair in a raised position.

The left side elevational view of the chair is omitted because it is a mirror image of the right side elevational view.

Throughout the Figures, portions represented by broken lines are not parts of the claimed design; the dot-and-dash lines show the boundaries of the claim and form no part thereof.
